UNITED STATES PATENT OFFICE.

ALEXANDER P. WHITE, OF CALDWELL, NEW JERSEY, ASSIGNOR TO THE GENERAL FIREPROOFING COMPANY, OF YOUNGSTOWN, OHIO, A CORPORATION OF OHIO.

EXPANDED METAL STRUCTURE.

No. 848,726.

Specification of Letters Patent.

Patented Feb. 12, 1907.

Application filed July 27, 1906. Serial No. 328,019.

To all whom it may concern:

Be it known that I, ALEXANDER P. WHITE, a citizen of the United States, and a resident of Caldwell, Essex county, State of New Jersey, have invented certain new and useful Improvements in Expanded Metal Structures, of which the following is a specification.

This invention relates to expanded metal structures, more particularly to reinforcing members suitable for embodiment in concrete and other masonry constructions.

The objects of the invention are to improve upon the construction of such members and increase their efficiency.

Further objects of the invention will hereinafter appear, and to these ends the invention consists of an expanded metal structure for carrying out the above objects embodying the features of construction, combinations of elements, and arrangement of parts having the general mode of operation substantially as hereinafter fully described and claimed in this specification and shown in the accompanying drawings, in which—

Figure 1 is a top plan view of a blank. Fig. 2 is a side elevation of the blank expanded. Fig. 3 is a side elevation of a similar expanded structure. Fig. 4 is a top plan view of another blank. Fig. 5 is a side elevation of the blank expanded. Fig. 6 is a side elevation of a similar construction. Fig. 7 is a side elevation of a modified form of reinforcing member. Fig. 8 is a side elevation illustrating the reinforcing member in use. Figs. 9, 10, 11, and 12 are detail transverse sections views of blanks.

Referring to the drawings, in Fig. 1 a blank is shown from which the reinforcing member or expanded metal structure is made. It is obvious that the blank itself may either be a flat sheet of metal, as shown in Fig. 9, or it may be provided with slats or ribs A of any desired cross-section, as shown in Fig. 11. Figs. 10 and 12 show ribs B, C of modified constructions. In Fig. 1 the ribs or bars D are round in cross-section and connected by the web portion E, which is suitably slotted at F and G to form connecting members H. These connecting members H are connected at each end to the blank, so that the ribs D may be separated, as shown in Fig. 2, to form a reinforcing member.

Preferably the slits F and G are provided in the blank extending in each direction from the center, so that a double member is formed, as shown in Fig. 2, when the rods or ribs D are separated; but the reinforcing member as a whole may be single instead of double—that is, one-half of the structure shown in Fig. 2, for instance, may be used. Preferably, also, the ties H are cut so that they become longer proceeding from the center outwardly. Therefore the top members D' are not parallel to the lower member D, but in this instance slant toward the center either in a straight or curved line. If desired, the inner ends I of the top members D' may be connected by a suitable sleeve J, held in position in any desired manner.

In Fig. 3 a structure is shown in which the upper members K and lower member L are not thickened; but the structure is constructed from a sheet of metal of the same thickness throughout. If desired, the inner ends K' of the members K may be connected by overlapping plates O.

In Fig. 5 a truss-like structure is constructed out of a blank which is cut as shown in Fig. 4. The blank comprises the web portions P, connected by the ribs or rods Q. The slits R and S are so cut that ties or connecting members T are formed, which connect the rods Q and preferably increase in length from the center outwardly from each side of the center, so that a truss-like member is formed, as shown in Fig. 5, when the bars are separated. If desired, the truss-like structure may be formed from a blank of the same thickness throughout, as shown in Fig. 6. In both Figs. 5 and 6 the upper members Q are cut so that the cross-sectional area increases from the center in the direction of the ends. The lower members Q diminish in cross-section as the ends are approached. This disposal of the metal is very desirable to provide for the stresses when the metallic structure is used to reinforce concrete.

In Fig. 7 the slits in the blank are so cut that the ties or connectors U are staggered when the side or bottom members V of the blank are moved endwise to open out the structure.

My invention relates to that class of expanded metal structures in which the expansion resulting from the opening out of a

slitted blank makes a structure which is thicker than the original blank in contradistinction to the other well-known forms in which the expansion results in an increased superficial area of metal.

In my invention dispose the metal of the blank in different planes, the uncut strips which are in different planes being connected with ribs or slats which form the lattice portions of a truss.

I do not claim to be the original inventor of expanded metal trusses, there being a full disclosure of the basic idea of the expanded-metal truss in the patents to C. B. White, Nos. 689,938 and 670,827. My present invention, however, relates to certain improvements and modifications on said patents, which modifications are of great importance in the practice of the art for which these expanded truss-like structures are available, particularly the reinforcement of concrete bodies designed to carry heavy loads and resist certain stresses. For instance, it is well known that the stresses in a concrete beam or slab follow certain well-defined lines, and the object of my invention is to provide for these stresses with a proper disposition of the metal when embodied in the concrete construction. In a beam or girder, for example, the tensional stress at the ends will be near the top; but it will descend as it approaches the middle of the beam, from which point it will ascend to the opposite end. Hence my aim is to provide a metallic structure of ascending and descending members of a truss-like form to accommodate the lines of tension when the metal is embedded in concrete, one important feature being the fact that my invention permits these cooperating truss-like units oppositely arranged to be made out of a single integral piece of metal. Furthermore, any desired number of the units shown may be united in the structure. In such cases where the use of structures containing these truss-like units is desirable the greatest tensional strain will be in the lower part of the center of the beam. Therefore more metal is required immediately at the center, and this requirement can be readily met by leaving uncut and undisturbed the metal in the central portion of the blank. Provision can be also made for the variation in the stresses from the center toward the ends. For example, if it is desirable to increase the metal in the top member from the center toward the ends this result can be readily accomplished as shown in Fig. 4, representing the blank, and by Fig. 6, representing one of the forms of the finished product, this distribution of the metal being effected by suitable arrangement of the cuts in the blank. In like manner the size of the slats which provide for certain stresses is also regulated.

For the purpose of simplicity and clear-

ness in distinguishing the different parts of these structures in the claims I prefer to call the longitudinal parts "members," these members being, for instance, the parts represented in Fig. 2 by the letters 'D' and 'D'. The shorter parts which connect or tie these members together I designate as "slats" or "tie-pieces," as shown by the letter H in Fig. 3.

While these expanded metal truss-like structures may be used for masonry, as described, the invention is not limited to such use, as they may be found very desirable for many other purposes.

I claim, and desire to obtain by Letters Patent, the following:

1. An expanded metal construction comprising outer members extending at an angle to each other connected by a plurality of tie-pieces, the entire structure made of a single piece of metal.

2. An expanded metal construction comprising outer members extending at an angle to each other connected by a plurality of tie-pieces which progressively increase in length, the entire structure made of a single piece of metal.

3. An expanded metal construction comprising outer members extending at an angle to each other, and tie-pieces integrally connected to each member, the entire structure made of a single piece of metal.

4. An expanded metal construction comprising outer members extending at an angle to each other, and tie-pieces integrally connected to said members and extending substantially parallel to each other between said members, the entire structure made of a single piece of metal.

5. An expanded metal construction comprising a longitudinal member in one plane, a plurality of longitudinal members in another plane, both arranged at an angle to said first member, and tie-pieces connecting said first member with the other members, the entire structure made of a single piece of metal.

6. An expanded metal construction comprising a longitudinal member or base, a plurality of members arranged at an angle to the base and extending downwardly and inwardly toward the central portion of the base, and tie-pieces connecting said base with said upper members, the entire structure made of a single piece of metal.

7. An expanded metal construction comprising a longitudinally-extending member or base, longitudinal members in a different plane from the base, and sets of diverging tie-pieces connecting the base with said members, the entire structure made of a single piece of metal.

8. An expanded metal construction comprising a longitudinally-extending member or base, longitudinal members in a different

plane from the base and arranged end to end, and inclined in opposite directions from the center and sets of tie-pieces connecting the base with said members, the entire structure 5 made of a single piece of metal.

9. An expanded metal construction comprising a longitudinal member or base, longitudinal members in a different plane from the base and arranged end to end, and inclined in opposite directions from the center and sets of diverging tie-pieces connecting the base with said members, the entire structure made of a single piece of metal.

10. An expanded metal construction comprising a longitudinally-extending member or base, longitudinal members in a different plane from the base increasing in cross-sectional area from the center outwardly, and sets of tie-pieces connecting the base with 15 said members.

11. An expanded metal construction comprising a longitudinally-extending member or base decreasing in cross-sectional area in each direction from the center outwardly, 25 longitudinal members in a different plane from the base increasing in cross-sectional area from the center outwardly, and sets of tie-pieces connecting the base with said members.

30 12. An expanded metal construction comprising a longitudinally-extending member or base, longitudinal members, each extending at an angle to said base, and sets of tie-pieces connecting the base with said members, all of said parts being integral.

13. An expanded metal structure consisting of a main base member and a second member in another plane, the said second member being inclined in opposite directions 40 from the center, so that the distance between the second member and the base member increases from the center toward the ends, the two members being tied together with slats, the whole structure being integral.

45 14. An expanded metal structure, consist-

ing of a main longitudinal straight member, and an inclined second member in a different plane, both members being connected together with slats or ribs, the whole structure being integral.

15. An expanded metal structure, consisting of two main members in different planes connected with slats, the main members diverging so that the distance between them is greater at one end than at the other end, the 50 whole structure being integral.

16. An expanded metal structure, consisting of a main longitudinal member, two members in another plane, said two members being oppositely inclined so that the distance 60 between them and the main longitudinal member increases as the outer ends are approached, the inclined members being tied to the main member with slats, the whole structure being integral.

17. An expanded metal structure, consisting of a main member serving as a base having a portion in the center uncut, and two members oppositely inclined from the central uncut portion, so that the distance 70 between them and said main base member increases toward the outer ends, the said two members being connected with the main base member by slats, the whole structure being integral.

18. An expanded metal structure, consisting of a plurality of main members in one plane connected with a main member in another plane, the said members being connected with slats which increase in length 80 progressively from one end to the other end, the whole structure being integral.

In testimony whereof I have signed this specification in the presence of two subscribing witnesses.

ALEXANDER P. WHITE.
